CLAIM

(52) **U.S. Cl.** **D6/502; D6/367**

I claim the ornamental design for a portion of a chair back for dental patients, as shown and described.

(58) **Field of Classification Search** D6/334–336, D6/360, 361, 365, 367, 379, 500–502; D24/178, D24/183; 297/188.01, 316, 300.1, 330, 391,

DESCRIPTION

297/344.15, 344.17, 409

See application file for complete search history.

(56) **References Cited**

FIG. 1 is a front perspective view of a portion of a chair back for dental patients.

U.S. PATENT DOCUMENTS

FIG. 2 is a rear perspective view of the portion of the chair back of FIG. 1.

1,210,223 A	12/1916	Silbert
1,685,599 A	9/1928	Fletcher
2,172,063 A	9/1939	Hara
2,278,890 A	4/1942	May

2,985,228 A *	5/1961	Golden
3,172,699 A *	3/1965	Naughton

FIG. 3 is a top view of the portion of the chair back of FIG. 1.

FIG. 4 is a right-side elevational view of the portion of the chair back of FIG. 1. The left-side elevational view is omitted as being a mirror image of the right-side elevational view.

FIG. 5 is a front perspective view of the portion of the chair back for dental patients shown in the context of an exemplary dental chair.

The broken lines in the Figures are for illustrative purposes only and form no part of the claimed design. Additionally, the bottom view is omitted as being devoid of surface ornamentation.
